UNITED STATES PATENT OFFICE.

JAMES G. MACLAREN, OF SYRACUSE, NEW YORK, ASSIGNOR TO THE LAMSON COMPANY, OF SYRACUSE, NEW YORK, A CORPORATION OF MASSACHUSETTS.

MESSAGE CARRIER.

Application filed March 19, 1926. Serial No. 95,876.

This invention relates to message carriers of the type used in pneumatic tube store service systems for the purpose of carrying messages, charges, etc. from one place to another. In such systems it is common to have tubes from various parts of the store all come into a central collecting and distributing station. Here the incoming carriers are sorted out, the cash carriers going to one place and the charge or message carriers elsewhere. Since various classes or kinds of messages or charge slips may require the attention of different authorizers, department heads, etc., they must be assorted by a despatcher at the central station, but the process of assorting and distribution of the carriers is normally quite a tedious one as it requires the opening of each of the carriers and the examination of the contents thereof before the despatcher can determine as to their destination.

The present invention is designed to facilitate and speed up this process of distribution by providing a window in the side of the message carrier through which the nature of the contents can be quickly seen. To facilitate assortment, the papers, when placed in the carrier, may be folded up in such a way that the character of the message or the addresses may be read through this window, although other means of identification, for example distinctive color may obviously be resorted to.

The invention will be best set forth by the detailed description which follows and the claims appended thereto. In the drawings:

Fig. 1 is an elevation of the improved carrier showing the window for exhibiting the charge slip or message;

Fig. 2 is a view of the device taken at right angles to the view of Fig. 1 and partly in section to show the internal construction; and

Fig. 3 is a section on the line 3-3 of Fig. 2.

Referring to the drawings, the carrier preferably comprises concentric telescoping shells 1 and 5 respectively, the inner shell 5 being closed at one end. A head 2 is attached to the closed end of the shell 5, said head being of usual type and comprising a felt bumper 3. This head 2 is furnished with a driving washer 4.

The outer shell is open at both ends, abutting the bumper 3 at one end, and has a head

2^a at its opposite end. This head comprises an annular bumper 3^a which encircles the inner shell 1 and is held in place by an out-turned flange 1^a at the open end of the inner shell and a flange 3^b at the end of the outer shell. One or more rivets 6 hold the inner and outer shells in assembled relation. Shells 1 and 5 are provided with registering openings 7 and 8 respectively constituting a window through which the contents of the device can be seen. The inside shell 5 is provided with a raised portion 9 to which one limb 11 of a flat spring is secured by any suitable means, for example by rivets 11^a.

The spring 10 preferably consists of a ribbon of spring steel comprising the limb 11 as aforesaid, bent at 10^a to provide a second limb 12 substantially parallel to the limb 11 and which normally presses against the inner surface of the carrier at the sides 75 of the widow. Preferably the bend 10^a is directed toward the open end of the carrier body and the free end of the limb 12 is bent toward the axis of the carrier so as to facilitate interposition and withdrawal of a paper slip from between the limb 12 and the wall of the carrier. Papers 13 are indicated in Figs. 1 and 2 in position immediately below the opening so that their nature may be observed readily through the window. These 80 papers are held in this position by the portion 12 of the spring 10 as clearly shown in Fig. 2, the paper being readily inserted or withdrawn through the open end of the carrier.

The improved message carrier is simple in construction and is adapted to have its contents easily and quickly read without withdrawing them from the carrier, thus facilitating distribution as explained above.

The embodiment of the invention described herein is merely for the purpose of illustration, and I do not intend to be limited except by the scope of the appended claims.

I claim:

1. A message carrier for pneumatic tube systems comprising a tubular shell open at one end and having a constantly open lateral window through which the contents 105 can be inspected.

2. A message carrier for pneumatic tube systems comprising a tubular body open at least at one end, said body being provided with heads at its opposite ends and with a 110

permanently open lateral window through which the contents of the carrier can be inspected.

3. A message carrier for pneumatic tube systems having a permanently open lateral window, and a spring member mounted inside of said carrier substantially opposite to said window for positioning the contents of the carrier with respect to said window so that their nature can be determined without removal from the carrier.

4. A message carrier for pneumatic tube systems having a permanently open lateral window, and a spring member mounted inside of said carrier, said spring member having a portion parallel to the axis of said carrier and adjacent to said window for pressing the contents of the carrier against the inner surface of the carrier bordering said window so that the character of the contents of the carrier may be seen through the window.

5. A message carrier for pneumatic tube systems comprising a tubular body open at one end and having a head at one end, the body having a lateral window, a flat spring comprising a limb affixed to the inner surface of the body at a point substantially diametrically opposite to the window, and a limb substantially parallel to said first limb but disposed adjacent to said window and normally resiliently engaging the inner surface of the body bordering the window.

6. A message carrier for pneumatic tube

systems comprising a tubular body open at one end and having a permanently open window in its side wall, and a spring clip within the body of the carrier, said spring clip comprising a flat ribbon of resilient material bent to provide spaced substantially parallel limbs, one of said limbs being anchored to the wall of the carrier and the other limb normally pressing against the inner wall of the carrier at points adjacent to the window, the bend of the spring being directed toward the open end of the tubular body.

7. A carrier for pneumatic dispatch systems comprising a shell open at one end and having a sight opening in the side wall thereof, and means for holding a slip of paper against the inner surface of the shell in display relation to said sight opening.

8. A carrier for pneumatic dispatch system comprising a shell open at one end and having a sight opening in the side wall thereof, and a spring member mounted in the shell and accessible at the open end thereof to provide for passing a slip of paper between the spring member and the inner surface of the side wall of the shell, said spring member operating to hold the slip in display relation to said sight opening.

Signed by me at Syracuse, New York, 65
this 16th day of March, 1926.

JAMES G. MACLAREN.
